UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

OIL STILL.

Application filed August 10, 1923. Serial No. 656,671.

This invention relates to improvements in the construction and operation of oil stills, and more particularly of oil cracking stills, whereby the efficiency and capacity of the 5 still is increased.

The invention is of special value for cracking petroleum hydrocarbons of high boiling point, such as gas oil and the like, in pressure stills to form more volatile or lighter 10 hydrocarbons therefrom, such as those which constitute commercial gasoline.

Pressure stills and other stills for cracking oil are heated by furnaces in which coal, gas or oil is burned and, for economy of fuel 15 consumption, it is desirable that the fuel be burned in the furnace with the least amount of excess air and the maximum furnace temperature. Excessive temperatures are, however, objectionable in the heating chambers 20 of oil cracking stills. Carbon is formed during the cracking operation and tends to deposit on the side of the tubes or heating surfaces of the still, and such a layer of carbon or of heavy tar is a poor conductor of 25 heat and insulates the metal surfaces from the oil on the inside, with the result that the temperature of the metal is increased, and this increase of temperature becomes excessive with increased thickness of the carbon 30 deposit. The overheating of the still or of the tubes or heating elements of a cracking still, and the resulting increased tendency of carbon formation, tend to give hot spots, and involve a considerable element of danger 35 or hazard to life and property due to the possible bursting of a tube which has become overheated and burned. Inasmuch as the pressure in cracking stills is frequently maintained at pressures around 100 40 pounds per square inch and may be maintained considerably higher, for example, around 600-700 pounds, any break or rupture is followed by a disastrous fire.

In an oil cracking still the tubes or other 45 heating surfaces most exposed to the heat of the furnace will be the first to suffer. The danger of overheating such tubes or surfaces can be decreased by reducing the fuel consumption, but this in turn reduces the capacity of the still, while, if the still is driven hard to increase its capacity by increasing the fuel consumption, the danger of overheating is greatly increased.

According to the present invention, danger of overheating is avoided or minimized, and 55 a heating action of increased uniformity is obtained, while the invention nevertheless enables the still to be operated with increased efficiency and increased capacity of output.

According to the present invention, I return and admix with the products of combustion in the firebox or between the firebox and the heating chamber of the still, a part 60 of the hot flue gases from near the outlet of the heating chamber. In addition I preheat 65 air by heat interchange with the flue gases escaping from the still and utilize the pre-heated air for promoting combustion in the firebox. By preheating the air, a more intense combustion is obtained at a correspondingly increased temperature, but by admixing 70 the products of combustion with the returned flue gases the increased temperature of combustion is modified and the products of combustion are cooled before they come in 75 contact with the heating surfaces of the still. The objections incident to excessive temperatures and increased combustion are thus avoided so that advantage can be taken of the increased heating effect of such temperatures and combustion. By regulating the 80 amount of the flue gases returned and admixed with the products of combustion, the temperature of the heating gases can be reduced from the highest temperatures of the 85 firebox to a predetermined lower temperature before the gases come in contact with the heating surfaces of the still. The flue gases which are returned are at approximately 90 the temperature of the waste gases leaving the heating chamber, and, while these gases serve to reduce the high temperatures obtained with the preheated air in the firebox, they reduce it only a part of the way down to the temperature of the returned 95 gases. Accordingly, the dilution of the products of combustion is not accompanied 100 by a reduction in efficiency such as accompanies the burning of fuel with an excessive amount of cold air, or such as would accompany the introduction of cold gases. On the contrary, the reduction in efficiency commonly incident to the use of cold air in the firebox is avoided by the use of preheated air, and the efficiency of the heating operation thereby improved; while the operation 105

is further improved and danger of overheating avoided or minimized, and a more uniform heating effect obtained, by the return of the flue gases for admixture with the products of combustion.

In my prior application Ser. No. 532,482, filed January 28, 1922, and my companion application, Ser. No. 656,672 filed August 10, 1923, I have described and claimed the improved method and apparatus in which a part of the flue gases are returned for admixture with the products of combustion to lower the temperature of the products of combustion before they come in contact with the heated surfaces of the still. The present invention includes the improvement of said prior applications and further improves the operation of the stills by increasing their efficiency and capacity. In addition to returning a part of the flue gases, the present invention provides for utilizing the flue gases after they have served their purpose in heating the still, by preheating air therewith and supplying the preheated air for promoting the combustion and improving the heating operation. This improved heating operation which would otherwise be objectionable because of the increased temperatures is thus taken advantage of and its objections overcome. The increased intensity of combustion and the increased temperatures obtained by the use of the preheated air enable an economy in fuel consumption to be obtained with like heating effect, or, with the same fuel consumption, cause an increased heating effect; while the moderating of the high temperatures by the admixed hot flue gas gives a more uniform heating effect. decreases the temperature of the gases first coming in contact with the still, increases the velocity of the gases passing over the heating surfaces, and gives an increased heating effect at parts of the still more remote from the firebox.

The invention as above pointed out is of more or less general application to oil stills where overheating is objectionable and where increased efficiency of operation and increased output, without objectionable overheating, are desired. The invention is of special value, however, in conjunction with oil cracking stills, for reasons above pointed out.

The oil cracking stills to which the invention is applicable may be either stills of the shell type, or tube stills; and, in the case of tube-stills, the stills may be circulatory stills where the oil is circulated from a large supply tank through the heating tubes and back to the supply tank, or it may be a tubular still in which the oil is passed in a single pass through the coil without recirculation. The invention is particularly advantageous in connection with such tubular cracking stills where the heated gases come in contact

with a part of the tubes and subsequently pass over other tubes or other portions of the same tubes before escaping to the stack.

The charging stock employed in the cracking stills can be varied and the temperature and pressure maintained during the cracking operation may similarly be varied. In cracking heavier oils such as gas oil, pressures of around 90-125 pounds, for example, may be used, while in cracking lighter oils of the nature of kerosene, a considerably increased pressure may be employed, for example, around 300-325 pounds or much higher, e. g., around 600-700 pounds. The cracking stills may be operated either to produce pressure distillate, or a so-called synthetic crude and, in the case of a tubular cracking still, the oil may be recirculated through the tubes or may pass therethrough in a single pass.

In the case of a tubular cracking still the tubes are advantageously arranged in a vertical heating flue and the heating gases introduced near the top of the flue and discharged near the bottom. By arranging the firebox on a level with the bottom of the tubes and by providing a bridge wall separating the firebox from the heating chamber, the tubes are protected from direct radiation and the flue gases may advantageously be introduced in the vertical flue between the firebox and the heating flue. The heat interchanger for preheating the air by contact with the flue gases may also be arranged in a vertical flue. By providing a sufficiently intimate contact of the flue gases with the entering air, the air can be preheated to a temperature approximating that of the flue gases escaping from the heating chamber and the flue gases in turn may be cooled to a relatively low temperature. In case the natural draft of the flue gases is not sufficient, this may be supplemented by forced draft, for example, by using a blower. The introduction of air may similarly be effected by the suction of the burner or the natural draft of the furnace, or it may be supplemented by forcing means such as a blower. The return of the flue gases from near the outlet of the heating chamber to the firebox, or to the flue intermediate the firebox and still, may similarly be effected by suitable circulating means such as a blower or steam jet.

The relative proportion of returned flue gas to fresh products of combustion can be varied and regulated as desired. The temperatures in the fire box which, without the preheating of the air, might be around 2400° F., may, with the preheating of the air, reach a much higher temperature; but the cooling effect of the flue gases returned, for example, at a temperature around 800° F., will serve to reduce such excessive temperatures to a temperature which will be suitable for the

heating of the still. The temperature of the gases first coming in contact with the heating tubes may, for example, be reduced to around 2000° F. by the admixture of flue gases in sufficient amount with the much higher temperature products of combustion from the firebox.

The invention accordingly provides for first obtaining an increased or more intense combustion and then taking advantage of this combustion by admixture of hot flue gases therewith to obtain an improved heating effect in the heating of the still, without objectionable overheating; while the heating operation is made more uniform, and an increased volume of heating gases passes through the heating chamber and in contact with the heating surfaces of the still with an increased velocity which increases the rate and efficiency of heat absorption and has the further desirable result or tendency of carrying soot and slag through the heating chamber rather than depositing it upon the heating surfaces.

The invention requires but little modification of furnace structures such as are commonly used in heating oil cracking stills. The flue gases may, for example, be returned through openings or flues in the walls, floors or lining of the furnace and a simple blower or steam jet may be used for regulating the amount of flue gases returned. The pre-heater for the air may similarly be arranged in the outlet flue or stack and connections made between the preheater and the burner or firebox in such a way as to supply the preheated air in the amount required for the combustion. The returned flue gas may also be returned and introduced around the walls of the firebox and bridge wall so as to protect or assist in protecting the arch or other parts of the furnace from the intense heat of combustion.

The increase in the rate of gas flow over the heating surfaces, while it increases the rate and efficiency of heat absorption, also increases the friction loss, while the passing of the flue gases and air through the pre-heater introduces additional friction, and, to maintain the same furnace draft it is necessary to have a somewhat increased draft at the still outlet. When this is provided, however, the capacity of the still will be increased and its efficiency will also be increased, while the still will nevertheless be protected from objectionable overheating.

The invention will be further described in connection with the accompanying drawings showing two types of oil stills with which the invention is combined. Both of these stills are tubular stills. The still illustrated in Fig. 1 is of the general construction and operation set forth in Patent No. 1,285,200, granted to the Sinclair Refining Co. November 19, 1918, on the application of

Edward W. Isom. The invention is of particular advantage, as above noted, in conjunction with this and other tubular cracking stills; but it will be understood that the invention is of more general application in its broader aspects.

In the accompanying drawings,

Fig. 1 shows a still of the general character above mentioned, partly in section and partly in elevation, the illustration being somewhat conventional and diagrammatic;

Fig. 2 is a vertical view partly in section and partly in elevation showing the furnace and cracking coil of a modified form of cracking still;

Fig. 3 is a sectional view taken on the line 3-3 of Fig. 2; and

Fig. 4 is an enlarged sectional view showing one of the elements of the heat interchanger.

Referring first to the construction illustrated in Fig. 1, the still illustrated is a tubular cracking still of the general construction illustrated in said Patent No. 1,285,200. The still comprises the bulk supply tank or drum 1, the vertical heating tubes 2, the pipe connections 3, 4 and 5 connecting the bulk supply tank with the top and bottom headers or manifolds of the heating tubes, and the pump 6 for circulating the oil from the supply tank or drum through the heating tubes and back to the supply tank.

The still is provided with a reflux tower 7 connected with the vapor dome of the still by a vapor line 8 and arranged to return the condensed vapors through the pipe 9.

The firebox 10 is shown as having one or more oil burners 11, although the invention is not limited to the use of oil as the fuel. A vertical flue 12 connects the firebox with the upper end of the heating flue 16 in which the vertical heating tubes 2 are located. The bridge wall 13 is relatively high and separates the vertical flue 12 from the heating flue 16, while also protecting the heating tubes from direct radiation from the firebox. Arranged within the heating flue 16 are baffles 14 and 15 which cause the heating gases to pass over the heating tubes in three successive passes before they escape through the outlet connection 17. Baffles 18 protect the lower headers from direct contact with the heating gases.

A vertical flue 19 is connected with the outlet 17 at its lower end and with the stack connection 20 at its upper end. Arranged within this vertical flue are a series of tubes 21 which may be of the construction illustrated in Fig. 3. Air enters the chamber 22 at the top of these tubes and flows downwardly therethrough countercurrent to the upward flow of gases from the furnace. A flue 23 connects the lower ends of these air heating tubes and leads the pre-heated air to the connecting flue or flues 24.

and supplies the preheated air to the burners. With oil burners 11 such as those illustrated, these burners will have an entraining effect and will serve to draw the pre-heated air through the openings 25, and this induction of air may be supplemented by the stack draft or by supplemental forcing means.

Side connections, best shown in Fig. 3, 10 serve for the return of flue gases from near the outlet of the heating chamber to a point between the firebox and the first contact of the heating gases with the tubes. Two side connecting pipes are shown leaving the heating chamber at 26 near the outlet therefrom. Steam injectors 28 are shown for permitting the flow of these gases through the connecting pipes 27. These gases are discharged into the flue 29 and escape through 15 the opening or openings 30 at the bottom of the bridge wall and tend to rise along the front of the bridge wall and serve to protect the bridge wall, while they are gradually admixed with the products of 20 combustion and serve to cool them before they come into contact with the heating tubes 2.

In Fig. 2 the same or corresponding parts 30 are indicated by the same reference numerals as in Fig. 1. The general arrangement of the firebox, heating flue and preheater is the same as in the construction of Fig. 1. The heating tubes, however, are horizontally arranged and may be the tubes of a single 35 pass cracking still in which the oil enters at an inlet 31 at the bottom and passes up in a series of passes back and forth from one side of the still to the other through the heating tubes 32 until the cracked oil escapes 40 at 33. In the arrangement shown, the top and bottom headers 34 and 35 are each connected with ten tubes which are connected by end connections 36 with the intermediate 45 tubes so that a series of ten separate circulating streams is provided between the bottom and top headers. When the heating coil is thus used as a single pass cracking coil, the oil heated therein may discharge 50 into a chamber maintained at the same pressure and in which further cracking takes place, or the cracked oil may discharge into a vaporizing chamber or into a cooler or condenser maintained either at the same 55 pressure or at atmospheric pressure or at a predetermined intermediate pressure.

The heat interchanger for preheating the air by contact with the flue gases should be of a construction which permits effective heat transfer. The construction of heating 60 tube shown in Fig. 3 enables such an intimate heat transfer to be obtained. These tubes are made of sheet metal and have a minimum thickness, for example, of 5/64 of an inch. With tubes having such exceedingly thin metal walls it is possible to arrange a

large number of tubes and a corresponding number of spaces therebetween so that a very large surface of heat interchange is provided between the down-flowing air and the up-flowing flue gas. This enables the 70 air to be preheated effectively to a temperature approximating that of the escaping flue gases. By returning such preheated air and utilizing it for the combustion, the efficiency and temperature of the combustion is increased, but this increased combustion is 75 neutralized by the returned flue gases so that the heating gases that come in contact with the tubes of the still are at a regulated temperature which will avoid objectionable 80 overheating of the tubes.

It will be noted that the general direction of the flow of the heating gases and oil is opposed so that the relatively cooler oil entering at the bottom of the tubes extracts 85 the heat from the partially cooled gases and the oil which has thus been heated is exposed to the hottest gases in the upper portion of the tubes, or in the upper tubes of Fig. 2. The temperature of these gases is, however, tempered so that objectionable 90 overheating is avoided, and the increased velocity of the gases will cause an increased amount of heat to be absorbed in the lower 95 passes of the heating flue.

In practice there may be a small leakage of air through the furnace structure and into the heating chamber, which results in the introduction of a certain amount of free oxygen into the furnace gases. This oxygen will 100 be heated by the gases with which it admixes and may serve to bring about a slight additional combustion, but this is independent of the main preheating effect obtained in the firebox by preheating the air required for combustion and supplying this preheated air to the firebox.

It will thus be seen that the present invention provides both for increasing and for decreasing the temperature in the furnace and that this increase and decrease are successive and are so combined that full advantage can be taken both of the increased temperature of combustion made possible by pre-heating the air, and of the lower temperature and increased gas volume and velocity made possible by admixing hot flue gases with the products of combustion before the heating gases are employed for heating the still. An increased heating effect, but nevertheless a mild heating effect, can thus be obtained, and the efficiency of the heating operation improved and the capacity of the still increased; and these improved results can be obtained without increased fuel consumption and without objectionable overheating of the still, as well as without the employment of supplemental equipment other than the preheater for preheating the air by contact with the flue gases and such ad-

ditional means as may be required to give the necessary draft or circulation of the air and gases through the apparatus.

I claim:

5. 1. The improvement in the heating of oil cracking stills in which oil is heated to the cracking temperature by hot products of combustion from a firebox passing externally over the oil heating surfaces of the still, which have previously passed over the heating surfaces of the still, and supplying the preheated air to the firebox for improving the combustion therein, whereby the temperature of combustion is increased by the 70 preheated air and the increased temperature is reduced before the heating gases contact with the oil heating surfaces by the admixture of the hot waste heating gases.
10. 2. The improvement in the heating of oil cracking stills in which oil is heated to the cracking temperature by hot products of combustion from a firebox passing externally over the oil heating surfaces of the still, which comprises admixing a portion of the hot waste heating gases which have previously passed over the heating surfaces with the products of combustion from the firebox before passing them over the heating surfaces 15 of the still, preheating air by heat interchange with waste heating gases not to be returned as a diluent, and supplying the air so preheated to the firebox for combustion of fuel therein.
15. 3. The improvement in the heating of oil cracking stills in which oil is heated to the cracking temperature by hot products of combustion from a firebox passing externally over the oil heating surfaces of the still, which comprises preheating air by heat interchange with waste heating gases and supplying the preheated air to the firebox for increasing the temperature of the products of combustion with which the recirculated waste gases are admixed.
20. 4. The improvement in the heating of oil cracking stills in which oil is heated to the cracking temperature by hot products of combustion from a firebox passing externally over the oil heating surfaces of the still, which comprises diluting the hot products of combustion from the firebox with recirculated waste heating gases prior to bringing the heating gases into contact with the oil heating surfaces, preheating air by heat interchange with the waste heating gases and supplying the preheated air to the firebox for increasing the temperature of the products of combustion with which the recirculated waste gases are admixed.
25. 5. The improvement in the heating of oil cracking stills in which oil is heated to the cracking temperature by hot products of combustion from a firebox passing externally over the oil heating surfaces of the still, which comprises supplying preheated air to the firebox for combustion of fuel therein, reducing the temperature of the resulting products of combustion from the firebox by admixing hot waste heating gases therewith, 30 passing the resulting gaseous mixture over the oil heating surfaces of the still, and subsequently passing the waste heating gases not to be again admixed with the products of combustion from the firebox in heat interchange relations with air to be supplied to the firebox for combustion of fuel therein.
35. 6. The improvement in the heating of oil cracking stills in which oil is heated to the cracking temperature by hot products of combustion from a firebox passing externally over the oil heating surfaces of the still, which comprises supplying preheated air to the firebox for combustion of fuel therein, reducing the temperature of the resulting products of combustion from the firebox by admixing hot waste heating gases therewith, 40 passing the resulting gaseous mixture over the oil heating surfaces of the still, and subsequently passing the waste heating gases not to be again admixed with the products of combustion from the firebox in heat interchange relations with air to be supplied to the firebox for combustion of fuel therein.
45. 7. The improvement in the heating of oil cracking stills in which oil is heated to the cracking temperature by hot products of combustion from a firebox passing externally over the oil heating surfaces of the still, which comprises preheating air by heat interchange with the hot waste heating gases which have previously passed over the heating surfaces and supplying the preheated air to the firebox for increasing the temperature of the products of combustion with which the hot diluent gases are admixed.
50. 8. The improvement in the heating of oil cracking stills in which oil is heated to the cracking temperature by hot products of combustion from a firebox passing externally over the oil heating surfaces of the still, which comprises increasing the temperature of the products of combustion from the firebox by supplying preheated air to the firebox, then decreasing the temperature of the products of combustion from the firebox by admixing recirculated waste heating gases therewith, passing the resulting gaseous mixture over the oil heating surfaces, and preheating the air supplied to the firebox by heat interchange with the hot waste heating gases escaping from the still, the recirculated hot waste heating gases being returned immediately after passing over the oil heating surfaces and being at approximately the temperature of the heating gases 130
55. 9. The improvement in the heating of oil cracking stills in which oil is heated to the cracking temperature by hot products of combustion from a firebox passing externally over the oil heating surfaces of the still, which comprises recirculating a part of the hot waste heating gases which have previously passed over the heating surfaces and admixing them with the hot products of combustion from the firebox to give a gaseous mixture of reduced temperature, passing the resulting gaseous mixture over the heating surfaces of the still, preheating air by heat interchange with hot waste heating gases 60
60. 10. The improvement in the heating of oil cracking stills in which oil is heated to the cracking temperature by hot products of combustion from a firebox passing externally over the oil heating surfaces of the still, which comprises recirculating a part of the hot waste heating gases which have previously passed over the heating surfaces and admixing them with the hot products of combustion from the firebox to give a gaseous mixture of reduced temperature, passing the resulting gaseous mixture over the heating surfaces of the still, preheating air by heat interchange with hot waste heating gases 65

employed in heat-exchange with the air for preheating it.

8. The improvement in the heating of tubular oil cracking stills in which oil is heated to the cracking temperature by hot products of combustion from a firebox passing externally over the oil heating tubes of the still, which comprises passing the heating gases from the firebox over the tubes of 10 the still in a series of passes, returning part of the heating gases leaving the last pass for admixture with the hot products of combustion from the firebox before introducing them into the first pass, preheating air by 15 heat interchange with waste heating gases leaving the last pass, and supplying the preheated air to the firebox for increasing the temperature of the products of combustion with which the returned gases are ad- 20 mixed.
9. The improvement in the heating of oil cracking stills in which oil is circulated from a bulk supply through heating tubes and back to the bulk supply and in which 25 the oil circulating through the heating tubes is heated to the cracking temperature by hot products of combustion from a firebox passing externally thereover, which comprises passing the heating gases from the 30 firebox over the heating tubes, returning part of the hot waste heating gases which have passed over the heating tubes and admixing them with the hot products of combustion from the firebox to cool the latter 35 prior to passing the admixture over the heating tubes, preheating air by heat interchange with the hot waste heating gases and supplying the preheated air to the firebox for the combustion of fuel therein.
- 40 10. The improvement in the heating of oil cracking stills in which the oil is circulated in a single pass through heating tubes and in which the oil is heated to the cracking temperature in the heating tubes by hot 45 products of combustion from a firebox passing externally thereover, which comprises passing the heating gases over the heating tubes in a generally countercurrent direction to the flow of oil, recirculating a part 50 of the hot waste heating gases which have previously passed over the heating tubes and admixing it with the hot products of combustion from the firebox to give heating 55 gases of lower temperature before passing the heating gases over the heating tubes, and increasing the temperature of the hot products of combustion from the firebox with which the returned gases are admixed by preheating air by heat interchange with 60 waste heating gases not to be again recirculated over the oil heating surfaces and supplying the preheated air to the firebox for the combustion therein.
- 65 11. The improvement in the heating of oil cracking stills in which the oil is circulated

in a single pass through heating tubes and in which the oil is heated to the cracking temperature in the heating tubes by hot products of combustion from a firebox passing externally thereover, which comprises 70 passing the heating gases over the heating tubes in a generally countercurrent direction to the flow of oil, recirculating a part of the hot waste heating gases which have previously passed over the heating tubes and ad- 75 mixing it with the hot products of combustion from the firebox to give heating gases of lower temperature before passing the heating gases over the heating tubes, and in- 80 creasing the temperature of the hot prod- ucts of combustion from the firebox with which the returned gases are admixed by preheating air and supplying the preheated air to the firebox for the combustion there- 85 in, the preheating of the air being effected by heat interchange with hot waste heating gases which have passed over the heating tubes.

12. An oil cracking still having a heating chamber, oil heating surfaces adapted to be externally heated therein, a firebox, means for conducting hot products of combustion from the firebox to the heating chamber, means for diluting and cooling the hot products of combustion from the firebox with hot waste heating gases from the heating chamber before entrance into the heating chamber, and means including a heat interchanger for preheating air by heat interchange with hot waste heating gases not returned to the heat- 10 ing chamber and for supplying the air so preheated to the firebox for combustion.

13. An oil cracking still having a heating chamber, oil heating surfaces adapted to be externally heated therein, an inlet and an outlet to the heating chamber, a firebox com- 10 municating with the heating chamber at the inlet, a flue communicating with the outlet of the heating chamber, a flue connecting the heating chamber near the outlet with the firebox and means for causing a return of a portion of the waste heating gases from the heating chamber through said flue to the firebox, and means including a heat inter- 11 changer arranged for preheating by heat interchange with waste heating gases in the first named flue and for supplying the air so preheated to the firebox, whereby the tem- 12 perature of combustion in the firebox is increased and this temperature is decreased by the admixture of returned waste heating gases.

14. An oil cracking still having a heating chamber, oil heating surfaces adapted to be externally heated therein, an inlet and an outlet to the heating chamber, a firebox com- 13 municating with the heating chamber at the inlet, means for returning hot waste heating gases from near the outlet of the heating chamber and admixing them with the hot

products of combustion from the firebox before the heating gases come in contact with the heating surfaces of the still in the heating chamber, a heat interchanger arranged 5 for preheating air by heat interchange with the waste heating gases from the outlet of the heating chamber, and means for introducing the preheated air into the firebox.

15. A tubular oil cracking still having a 10 heating chamber, oil heating tubes adapted to be externally heated therein, a firebox communicating with the heating chamber, means for admixing hot waste heating gases from the heating chamber with the products 15 of combustion from the firebox at a point between the firebox and the heating chamber, and means including a heat interchanger for preheating air by heat interchange with the remainder of the hot waste heating gases 20 from the heating chamber and for supplying the air so preheated to the firebox for combustion.

16. A tubular oil cracking still having a 25 heating chamber, oil heating tubes adapted to be externally heated therein, a firebox communicating with the heating chamber, means for supplying preheated air to the firebox for the combustion of fuel therein,

and means for admixing hot waste heating gases from the heating chamber with the 30 products of combustion from the firebox at a point between the firebox and the heating chamber, the means for supplying preheated air including a heat interchanger arranged for subjecting the air to heat interchange 35 with hot waste heating gases from the heating chamber.

17. A tubular oil cracking still having a 40 heating chamber, oil heating tubes adapted to be externally heated and vertically arranged in the heating chamber, a firebox communicating with the upper end of the heating chamber, an outlet near the lower end of the heating chamber, a heat interchanger arranged for preheating air by heat 45 exchange with the hot waste heating gases from the outlet, means for supplying the preheated air to the firebox for the combustion of fuel therein, and means for returning hot waste heating gases from near the 50 outlet of the heating chamber and admixing them with the products of combustion from the firebox at a point between the firebox and the heating chamber.

In testimony whereof I affix my signature.
JOHN E. BELL.
